ROTATABLE ATTENUATOR FOR WAVE GUIDES

Arnold E. Bowen, Fair Haven, N. J., assignor to Bell Telephone Laboratories, Incorporated, New York, N. Y., a corporation of New York

Application December 11, 1946, Serial No. 715,589

1 Claim. (Cl. 178—44)

1

This invention relates to variable wave guide attenuators.

An object of the invention is to vary the attenuation of electromagnetic waves in a wave guide without changing their polarization.

Another object is to continuously vary the attenuation in a wave guide by rotation without concomitantly setting up undesirable reflections.

Another object of the invention is to continuously vary the attenuation of a wave without concomitantly changing the direction of its polarization vector, by continually suppressing quadrature cross components developed during the attenuation.

Another object of the invention is to attenuate waves in accordance with a trigonometric function of an angle of rotation.

Another object of the invention is to attenuate waves propagated bilaterally, i. e., in two opposite directions through a wave guide without changing their direction of polarization.

A feature of the invention is a rotatable attenuator for wave guides comprising a rotatable wave guide section connected intermediate to two stationary guide sections, the rotatable section being provided with a diametral attenuating plate extending longitudinally thereof, while the stationary sections are each provided with cross component suppressors.

Fig. 1 represents a rotatable attenuator in accordance with the invention.

Fig. 2 is an explanatory electric force vector diagram.

Fig. 3 illustrates a modification of the attenuator.

Wave guide attenuators have heretofore been disclosed, for example, in the United States Patent 2,197,122, issued April 16, 1940, to A. E. Bowen, in the United States Patent 2,197,123, issued April 16, 1940, to A. P. King, and in the United States Patent 2,151,157, issued March 21, 1939, to S. A. Schelkunoff.

The object of such attenuators in general is to attenuate dielectrically guided waves propagated within metallic pipe guides without simultaneously generating spurious reflections.

For more precise control of the propagation of waves in hollow pipe wave guides or similar systems, it is desirable to attenuate linearly polarized electromagnetic waves without affecting or changing the direction of polarization. In accordance with an embodiment of the invention, attenuation without change of polarization is achieved by means of a rotatable attenuator, wherein cross-polarization wave components de-

veloped in the bilateral or unilateral progress through the attenuator are absorbed, extinguished or otherwise suppressed.

In accordance with an embodiment of the invention, such a rotatable attenuator may comprise three tandem wave guide sections A, B, C, the intermediate one B being rotatably connected to the stationary sections A and C, respectively. The guide section B is provided with a diametral and longitudinally extending attenuating plate, having impedance matching terminations of notched or tapered form. Rotation of the intermediate guide section B through an angle θ will produce an attenuation equal to $\cos^2 \theta$ in the amplitude of a linearly polarized input wave. Cross components or quadrature polarizations are suppressed in the stationary sections A and C by lossy plates backed up with reflecting metallic septa.

Referring to Fig. 1, there is shown a two-way or bilateral attenuator comprising cylindrical wave guide sections A, B, C. Intermediate guide section B is rotatably coupled to the stationary end sections A and C by rotatable pipe joints as illustrated in Fig. 1.

The rotatable guide section B consists of a short length of cylindrical pipe, provided with a composite diametral attenuating plate 1 therein, extending longitudinally thereof and formed of three parts 2, 3, 4. Parts 3, 4 may be absorption plates of the type disclosed in the United States patent application of A. E. Bowen, Serial No. 486,013, filed May 7, 1943, now Patent No. 2,600,466, or the United States patent application of W. H. Hewitt, Jr., Serial No. 551,040, filed August 24, 1944, preferably providing more than 10 decibels of attenuation. The members 3, 4 are provided either with terminal, impedance matching, notched portions,

40 in length, where λ_s is the wavelength in the guide, or with terminations of tapered form as disclosed therein. Part 2 is a conductive septum plate greater than

45 $\frac{\lambda_s}{2}$ in length for reflecting a parallel component into the absorption plates 3, 4 for more effective attenuation.

50 The stationary guide sections A, C are identical. Each consists of a short length of cylindrical wave guide having a conductive septum 5 in-

55

tegrally associated with an absorption plate 6, the unit extending longitudinally thereof in a diametral plane.

Initially the guide sections A, B, C are lined up so that the plates 1 and 6, 6' are coplanar and $\theta=0$, whereby both the attenuation of linearly polarized waves transmitted therethrough is zero, and the direction of polarization is unaltered.

However, when intermediate guide section B is rotated through an angle θ and the attenuating plate 1 is inclined θ to the fixed, common plane 6-6', an input polarized wave entering section A perpendicular to conductive septum 5 will emerge from section C with its amplitude attenuated proportional to $\cos^2 \theta$ but with its polarization direction unchanged, as will be presently explained in greater detail.

In actual operation (see the vector diagram of Fig. 2) suppose an input wave E, polarized perpendicular to the plane of conductive septum 5, enters the attenuator (A, B, C) at the left. Since the septum 5 is perpendicular to E, the wave will emerge from section A unchanged and be incident on the intermediate guide section B. Here E may be resolved into two components in space quadrature, E_{11} , parallel to attenuating plate 1, and E_1 , perpendicular thereto. In the passage through section B, the parallel component E_{11} is fully absorbed by attenuating plate 1, while the perpendicular component E_1 passes freely thereover and into guide section C. From Fig. 2, it is apparent that

$$E_1 = E \cos \theta$$

$$E_{11} = E \sin \theta$$

The wave represented by E_1 , incident on stationary end section C, is resolvable again into two quadrature components with respect to the plane 5'-6'. The component parallel to septum 6' will be transmitted into the absorption plate 6' and dissipated therein, whereas the perpendicular component E' (Fig. 2C) will pass freely thereover and emerge. From Fig. 2C, it is apparent that

$$E' = E_1 \cos \theta = E \cos^2 \theta$$

In the resolution of vectors in guide sections B and C as described above, the parallel components encounter no discontinuities as they pass into all the absorption plates because of the impedance matching terminals thereon. Undesirable reflected waves are therefore not generated by the parallel components. Likewise, the quadrature components being unaffected by the perpendicular disposition of the absorption plates thereto suffer no reflections. Thereby, the wave in its progress through the attenuator encounters the same characteristic impedance irrespective of the angle θ through which section B is rotated and attenuation is achieved without reflection for both directions of transmission. Therefore in this system, an impedance match once established is maintained unchanged throughout all angular displacements of the absorption plates or expressed slightly differently, the impedance match is maintained whatever the attenuation introduced may be.

Comparing the input wave vector E and output vector E' , it is apparent that the polarization directions are alike, but the emergent vector E' is relatively reduced in amplitude, proportional to $\cos^2 \theta$. Accordingly, the rotation of section B through an angle θ , will produce attenuation proportional to $\cos^2 \theta$, without change of polarization

direction. Continuous rotation of section B will produce variable attenuation, but the polarization direction will remain invariant. Accordingly, the attenuation through rotatable attenuator A, B, C (Fig. 1) may be represented as:

$$\alpha = 20 \log_{10} \frac{1}{\cos^2 \theta}$$

where α (expressed in decibels) is defined, in general, equal to

$$20 \log_{10} \frac{E}{E'}$$

The values of α vs. θ in a rotatable attenuator A, B, C may be tabulated as follows:

θ	α
0	0.00
10	0.28
20	1.08
30	2.00
40	4.62
50	7.65
60	12.04
70	18.65
75	23.5
80	30.4
90	$\infty (>100 \text{ db})$

The attenuation at $\theta=90$ degrees depends on the length of the conductive septum 2, which preferably should be greater than

$$\frac{\lambda_g}{2}$$

where λ_g is the wavelength in the guide.

35 The specific construction of absorption plate 1 as disclosed in Fig. 1, yields a higher attenuation in a smaller space than heretofore. The reflecting action of septum 2, on the component parallel thereto causes the latter to suffer additional attenuation in absorption plate 3. Without the inclusion of septum 2, longer attenuating plates in section B would be required to provide sufficient attenuation.

Likewise, the conductive septa 5-5' by reflecting 45 the quadrature components back into the respective absorption plates 6-6', render the suppression of cross components more effective.

It should be noted with respect to two-way transmission that sections B and C are effective 50 in attenuating waves traveling from left to right, and section A further suppresses any cross components reversely directed. Correspondingly, a wave transmission directed from right to left, is attenuated in sections A, B, while reflected cross components are extinguished by section C.

The embodiment illustrated in Fig. 3 is a modification of the $\cos^2 \theta$ attenuator illustrated in Fig. 1, utilizing rectangular guide sections for cross component suppression.

60 The stationary sections A and C, Fig. 3, are each provided with an end, rectangular wave guide portion 26, so dimensioned and proportioned as to only transmit waves of one polarization, namely, waves polarized vertically and parallel to the small side b . The cross-sectional dimensions a, b of the rectangular wave guide 26 are such that

$$a > \frac{\lambda_a}{2}$$

$$b < \frac{\lambda_a}{2}$$

where λ_a is the wavelength in air.

65 A circular pipe guide portion 27, integral with

rectangular guide 26, contains therein in absorption plate 29 with a notched

$$\frac{\lambda_s}{4}$$

impedance matching terminal 28 at the end thereof facing section B. The rectangular guide 26 is connected to the circular pipe 27 by an impedance matching tapered transformer portion 28 whereby a gradual transition from rectangular to circular cross-section is produced, as shown in Fig. 3. In order to further compensate for residual impedance discontinuities between circular pipe 27 and rectangular pipe 26, a variable reactance screw S1 is provided in the latter.

The rotatable guide section B consists of a short length of cylindrical wave guide 29 provided with a diametral attenuating plate 21, extending longitudinally thereof and provided with

$$\frac{\lambda_s}{4}$$

impedance matching terminations 22. Rotatable joints are provided between rotatable section B and stationary sections A, C at the respective ends thereof as indicated in Fig. 3. Rotary motion through 90 degrees may be imparted to pipe 29 by milled ring 23, having screws 14 movable in slots 15.

The mode of operation of the embodiment shown in Fig. 3 is essentially similar to that described in connection with Fig. 1. The rectangular guide 26 passes the incident wave polarized parallel to the dominant E vector and suppresses cross components, parallel to a, the long side of the rectangle analogously to the septa 5-5' of Fig. 1. A rectangular guide dimensioned as above will support the propagation of one polarization parallel to b and cut off a quadrature polarization parallel to a.

The attenuator A, B, C of Fig. 3 may be inserted in a two-way transmission system and will operate in a manner similar to that previously described in connection with Fig. 1.

In both forms (Fig. 1 and Fig. 3), impedance matching at various sections of the attenuator A, B, C is provided by the notched terminal construction to prevent disturbing reflections being set up. Attenuation is achieved without alter-

ing the polarization vector and without reflection.

Although the attenuators have been described particularly in connection with wave guide transmission, it should be apparent to those skilled in the art that they may be applied in concentric line systems or in microwave radio relay link systems.

What is claimed is:

- 10 An attenuator for linearly polarized input microwaves comprising a plurality of axially aligned wave-guide sections having dissipative plates therein, said plates adapted to be aligned in a longitudinal plane perpendicular to said linear polarization to provide a zero attenuation, and means for rotating one of said plates with respect to said longitudinal plane, whereby the attenuation is a function of the angle of rotation, and means for maintaining the polarization of 15 the output waves unchanged with respect to the input polarization.
